(57) CLAIM

The ornamental design for a blueberry chewing gum, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a first embodiment of a blueberry chewing gum;

FIG. 2 is a front view thereof;

FIG. 3 is a side view thereof;

FIG. 4 is a top plan view of a second embodiment of a blueberry chewing gum;

FIG. 5 is a front view thereof;

FIG. 6 is a side view thereof;

FIG. 7 is a top plan view of a third embodiment of a blueberry chewing gum;

FIG. 8 is a front view thereof;

FIG. 9 is a side view thereof;

FIG. 10 is a top plan view of a fourth embodiment of a blueberry chewing gum;

FIG. 11 is a front view thereof;

FIG. 12 is a side view thereof;

FIG. 13 is a top plan view of a fifth embodiment of a blueberry chewing gum;

FIG. 14 is a front view thereof;

FIG. 15 is a side view thereof;

FIG. 16 is a top plan view of a sixth embodiment of a blueberry chewing gum;

FIG. 17 is a front view thereof; and,

FIG. 18 is a side view thereof.
